Primary Examiner — Terry Wallace(74) *Attorney, Agent, or Firm* — Cantor Colburn LLP(57) **CLAIM**

We claim, the ornamental design for a cooler, as shown and described.

DESCRIPTION

FIG. 1 is a front perspective view of a cooler, showing our new design in an exemplary embodiment;

FIG. 2 is a front perspective view of the embodiment shown in FIG. 1, the cooler being shown in another configuration;
FIG. 3 is a front elevation view of the embodiment shown in FIG. 1;

FIG. 4 is a rear elevation view of the embodiment shown in FIG. 1;

FIG. 5 is a top plan view of the embodiment shown in FIG. 1;
FIG. 6 is a bottom plan view of the embodiment shown in FIG. 1;

FIG. 7 is a side elevation view of the embodiment shown in FIG. 1; and,

FIG. 8 is another side elevation view of the embodiment shown in FIG. 1.

The broken lines are for environmental purpose only and form no part of the claimed design.

1 Claim, 7 Drawing Sheets(56)
